HARRY E. LEININGER, OF CHICAGO, ILLINOIS.

PAPER-HOLDING CLAMP.

1,218,675.

Specification of Letters Patent. Patented Mar. 13, 1917.

Application filed February 7, 1916. Serial No. 76,555.

To all whom it may concern:

Be it known that I, HARRY E. LEININGER, a citizen of the United States, residing at Chicago, Illinois, have invented certain new and useful Improvements in Paper-Holding Clamps, of which the following is a specification.

The essential object of this invention is to provide a clamping device for securing papers upon a holder or back. The back shown in the drawings is an ordinary board or other hard, flat body which affords a writing-surface, and the sheets of paper are adapted to be clamped in place upon said board by use of the hereinafter-described invention. The use of said board is merely illustrative, however, and other forms of backs or writing-surfaces may be employed. Backs and boards equipped with attachments for clamping or holding papers upon a writing-surface are old in the art and many varieties thereof are and have been stable articles of commerce for many years, and no invention broadly is claimed for the combination of a writing-surface and a spring-controlled or other device for clamping papers thereupon, but the invention does reside in the particular form of paper-clamping attachment shown in the drawings and described in the specification.

In the drawings, in which like numbers of reference represent like parts wherever they occur, Figure 1 is a perspective view of a board or base provided with a paper-holding clamp; Fig. 2 is a view of the clamping attachment, the board or base being removed; Fig. 3 is a detail of one of the clamping-arms; Fig. 4 is a detail of the other clamping-arm; Fig. 5 is a view at right angles to Fig. 2, looking downwardly from above in said Fig. 2; Fig. 6 is a detail taken on the line 6—6, Fig. 5, being upon an enlarged scale as compared with Fig. 5; Fig. 7 is a top plan view of a modified form of the invention; and Fig. 8 is a view at right angles to Fig. 7.

The board or base 1, which may be made of wood or any other suitable material hard and firm enough to provide a writing-surface, may be made of any desired size or shape. At or adjacent one end, the base 1 is provided with a countersunk portion or cavity, within which cavity 2 some of the movable parts are adapted to be received. The sheet or sheets of paper 3 to be clasped or clamped upon the base 1 are directly en-

gaged by the clamping-arms 4 and 5, which said clamping-arms 4 and 5 are either V-shaped or arcuate in cross-section, as best indicated in Figs. 2, 3, and 4 of the drawings. The clamping-arm 4 is secured to or integrally united with the swinging plate 6, while the clamping-arm 5 is similarly joined to the swinging plate 7. Plate 6 is provided with a perforation 8 through which the pintle or shaft 9 passes, the plate being freely revoluble around said pintle 9. Plate 7 is provided with a perforation 10 which is non-circular in shape and which fits over one part of the shaft 9, said shaft 9 at or near the point where it is engaged by plate 7, being shaped to correspond with the shape of the perforation 10. The shaft 9 and plate 7 may, however, be secured together in any manner to cause the plate 7 and the shaft 9 to rotate in unison.

One end of the shaft 9 is journaled in the ear or lug 11, the opposite end being secured to the flange 12, said flange 12 and said ear 11 being disposed in substantially parallel planes. A bed-plate 13 is provided, same being normally at right-angles to the members 11 and 12, all of said members 11, 12, and 13 being preferably united integrally together and being ordinarily made by stamping all of said parts from a single piece of sheet-metal. The ear or lug 11 depends from the bed-plate 13, as best shown at the bottom of Fig. 5 and at the front of Fig. 2, and the flange 12 similarly depends from the bed-plate 13, being connected therewith by narrow ribbons or webs 14, as best shown in Fig. 1. Part of the metal is removed at 15, thereby supplying a slot in the metal stamping adapted to register with the countersunk recess 2 in the base 1, thus permitting the plates 6 and 7 to revolve upon or about pintle 9 as an axis.

The pintle 9 is encircled by a helical spring 16, one end 17 of which passes through and is received within a perforation 17^a in the pintle 9. The other end of the helical spring 16 is bent to form an outwardly-extending arm 18 carrying a hook-like end 19, which hook-like end fits over the plate 6. If the plate 6, therefore, be rotated in a clockwise direction, Fig. 3, or in the counter-clockwise direction, Fig. 2, the coil part of the spring 16 will tighten as the hook-like end be elevated and said spring will normally act to return the plate 6 to normal or starting position indicated in Fig. 2, and

said spring, therefore, will normally keep the clamping-arm 4 pressed into engagement with the board or base 1 or into engagement with whatever sheet or sheets of paper may be placed upon the board. Similarly, if the plate 7 be rotated in a clockwise direction, Fig. 2, or counter-clockwise direction, Fig. 4, the shaft 9 is thus caused to revolve, thereby tightening the helical spring 16, which spring, accordingly, tends to keep the plate 7 and arm 5 in the position depicted in Fig. 2. The base or board 1 is preferably recessed at 20 so as to permit the bed-plate 13 to be flush with the surface of the board and thus afford a practically unbroken-writing surface. When it is desired to move the sheets of paper from the board or to insert new sheets, the operator will grasp the clamping-arms 4 and 5 with his fingers, elevate said arms, which move, of course, against the resistance of the spring, and thereafter permit said clamping-arms to return under the action of the spring to normal or starting position, in which position the clamping-arms 4 and 5 will engage the paper and hold same in place. Said clamping-arms 4 and 5 are preferably made arcuate or substantially arcuate in cross-section in order to present a curved edge to the sheet or sheets of paper, thus enabling the device to accommodate itself to piles of paper of any thickness without presenting a sharp or cutting edge to the paper as would be done should the clamping-arms 4 and 5 be made flat with squared or sharp edges.

In the modification shown in Figs. 7 and 8, the metal stamping which supports the pintle 9 is omitted for convenience, although it will be obvious that some suitable support for pintle 9 must be provided. Upon the pintle 9 is a boss 21 which is provided with an annular groove 22, and in said groove 22 are received the coils of the spring 23, which groove, accordingly, serves to prevent slipping or displacement of the spring. The ends 24 and 25 of the spring 23 are bent into hook-like form and said ends project through suitable perforations in the plates 26 and 27. Both of the plates 26 and 27 are freely revolute upon the pintle 9, and the spring 23 will normally actuate the plate 7 in a clockwise direction (Fig. 8), thus keeping the clamping-arms 4 and 5 normally pressed into engagement with the writing surface.

I claim as my invention:

1. A means for clamping papers comprising a bed-plate, a flange and an ear on opposite sides of said bed-plate and disposed at an angle thereto, a shaft extending from said flange to said ear and being revolutely received by the same, a pair of plates received upon said shaft, a clamping-arm projecting outwardly from each of said plates, and a spring coöperating with said shaft

and with each of said revolute plates and adapted to actuate said plates.

2. A means for clamping papers comprising a bed-plate, a flange and an ear on opposite sides of said bed-plate and disposed at an angle thereto, a shaft extending from said flange to said ear and being revolutely received by the same, a pair of plates received upon said shaft, a clamping-arm projecting outwardly from each of said plates, 75 and a spring coöperating with said shaft and with each of said revolute plates and adapted to actuate said plates, said bed-plate being provided with a slot or perforation through which said revolute plates are 85 adapted to move.

3. A means for clamping papers comprising a pair of revolute plates, a shaft about which same are adapted to revolve, a clamping-arm extending outwardly from each of said plates, and a spring mounted upon said shaft and adapted to actuate each of said plates.

4. A means for clamping papers comprising a pair of revolute plates, a shaft about 90 which same are adapted to revolve, a clamping-arm extending outwardly from each of said plates, and a spring mounted upon said shaft and adapted to actuate each of said plates, said clamping-arms being substantially arcuate in transverse section. 95

5. A means for clamping papers comprising a writing-surface, a pair of revolute members, a shaft in connection with which both of said members are adapted to revolve, a clamping-arm projecting from each of said members, and means adapted to actuate said members thereby to keep said clamping-arms normally in engagement with said writing-surface. 100

6. A means for clamping papers comprising a writing-surface, a pair of revolute members, a shaft in connection with which both of said members are adapted to revolve, a clamping-arm projecting from each of said members, and means adapted to actuate said members thereby to keep said clamping-arms normally in engagement with said writing-surface, said clamping-arm being provided with curved surfaces upon the 110 sides thereof which engage said writing-surface. 115

7. A means for clamping papers comprising a writing-surface, a pair of independently-actuatable plates which carry a clamping-arm, said clamping-arms being substantially parallel to said writing-surface, said plates being revolute around a common axis, and spring-like means adapted to actuate said plates thereby to force said clamping-arms into engagement with said writing surface. 125

8. A means for clamping papers comprising a writing-surface, a pair of independently-actuatable plates which carry a clamp- 130

ing-arm, said clamping-arms being substantially parallel to said writing-surface, said plates being revolute around a common axis, a spring connected with both of said revolute plates and adapted to actuate each of same, thereby to force said clamping-arms into engagement with said writing-surface.

9. A means for clamping papers comprising a writing-surface, a pair of independently-actuated plates which carry a clamping arm, said clamping-arms being substantially parallel to said writing-surface, said plates being revolute around a common axis, and spring-like means adapted to actuate said plates thereby to force said clamping-arms into engagement with said writing-surface, said clamping-arms being provided

with curved surfaces upon the sides thereof which engage said writing-surface.

10. A means for clamping papers comprising a writing-surface, a pair of independently-actuated plates which carry a clamping-arm, said clamping-arms being substantially parallel to said writing-surface, said plates being revolute around a common axis, and a spring connected with both of said revolute plates and adapted to actuate each of same, thereby to force said clamping-arms into engagement with said writing-surface, said clamping-arms being provided with curved surfaces upon the sides thereof which engage said writing-surface.
